UNITED STATES PATENT OFFICE

172,690

COMBINED SNACK AND BEVERAGE BAR

Stewart A. Sailor, Hinsdale, Ill., assignor to Virginia Sales, Incorporated, Hinsdale, Ill., a corporation of Illinois

Application August 26, 1953, Serial No. 26,594

Term of patent 14 years

(Cl. D2—3)

To all whom it may concern:

Be it known that I, Stewart A. Sailor, a citizen of the United States, resident of Hinsdale, Cook County, Illinois, have invented a new, original, and ornamental Design for A Combined Snack and Beverage Bar, of which the following is a specification, reference being had to the accompanying drawings, forming a part thereof, in which:

Fig. 1 is a front perspective view of a combined snack and beverage bar embodying my new design;

Fig. 2 is a side elevational view thereof;

Fig. 3 is a rear perspective view of the snack bar; and

Fig. 4 is a side elevational view thereof. The essential features of the design reside in the portions shown in full lines.

I claim:

The ornamental design for a combined snack and beverage bar, as shown and described.
